Patented June 17, 1919.

UNITED STATES PATENT OFFICE.

ALLEN C. ALLAN, OF CHICAGO, ILLINOIS.

WRENCH.

1,306,794.

Specification of Letters Patent. Patented June 17, 1919.

Application filed March 27, 1919. Serial No. 285,530.

To all whom it may concern:

Be it known that I, ALLEN C. ALLAN, a citizen of the United States, residing at Chicago, in the county of Cook and State 5 of Illinois, have invented certain new and useful Improvements in Wrenches, of which the following is a specification.

My invention pertains to wrenches, pliers, and the like, and aims to overcome some of 10 the defects of or to improve upon prior devices of this character, especially those having a main fixed or stationary clamping or work-engaging jaw and a companion clamping jaw slideable toward and from the other jaw. The leading or prime purpose of the 15 invention is to provide an appliance of this type, either fitted with one handle or a pair of handles in the form of pliers, which, while simple in structure and hence economical to manufacture, will have a wide range 20 of action or operative capacity, and in order to permit a long range of sliding movement of the reciprocating jaw to deal with articles such as nuts, screws, etc., of widely differing dimensions, without causing the handle or handles to assume undesirable and inefficient positions, I make the fulcrum or 25 pivot-pin of the one or more handles adjustable or shiftable to different positions. In 30 addition the structure is such that the movable jaw may be readily and easily detached from the appliance when desired thus permitting substitution of another of different form.

35 In order that those skilled in this art may understand the various advantages accruing from the employment of this invention I have illustrated several embodiments of the same in the accompanying drawing forming 40 a part of this specification and throughout the several views of which like reference characters refer to the same parts.

In this drawing:

Figure 1 is a face view of one form of 45 the improved wrench illustrating in dotted lines the position of the handle which permits release of the sliding jaw;

Fig. 2 is a central section through the same;

50 Fig. 3 is a fragmentary section showing a different arrangement of the fulcrum or pivot pin; and

Fig. 4 shows the invention applied to a pair of pliers.

55 Referring first to the wrench of Figs. 1

and 2 it will be seen that the appliance includes a body 10 comprising two, spaced, parallel, plate portions 11 and 12 having integral therewith a clamping-jaw 13 of usual and ordinary construction. Coacting with such jaw is another similar clamping-jaw 14 having a base portion 15 received and slideable between the parts 11 and 12 toward and from the main jaw. To hold these parts in position the element 15 is provided with a rib 16 accommodated and reciprocable in a groove 17 in the inner face of the part 11.

These two walls 11 and 12 are equipped with round registering fulcrum or bearing recesses or holes 18, 19 and 20 connected together by straight slots or passages 21 and 22 of less width than the diameter of any one of the three cylindrical bearings which they connect. Such aligned openings accommodate a single fulcrum or pivot-pin having 75 a central round part 23 revoluble or oscillatory in a similarly-shaped bearing 24 in an operating handle or lever 25 having at one end a rounded enlargement 26 of circular shape rockingly engaging a similar cavity or recess 27 in the part 15. This fulcrum or pivot-pin projects from opposite sides of the handle member and such cylindrical parts are flattened on opposite sides so that its transverse dimension at that point 80 is substantially equal to the width of the slots 21 and 22, the remainder of the pin being of the larger diameter of the bearings 18, 19 and 20 in any one of which the pin is adapted to fit, being shiftable at will from 90 one to the other. One end of such fulcrum-pin is equipped with a flat head 29 and its other end with a washer 30 and retaining cotter-pin 31.

Assuming that the pin is in any one of its 95 bearings 18, 19 or 20, the wrench may be used in the ordinary way by applying its jaws to the nut, bolt, screw or other article to be tightened or loosened, and then turned in the usual manner, the jaws having a 100 firm and secure grip on the nut or other member to which it is applied. In thus working the wrench when its jaws are tight on the nut, a pull on the handle causes the fulcrum-pin to press against that curved surface of its bearing remote from the jaw and there is no tendency for the pin to travel through either of the connecting passages into either of the other bearings, consequently there is no danger of the pin be- 110

coming displaced or of wearing away the corner portions of the walls of the bearings or connecting passages.

To turn or operate a nut of different size, 5 it may require that the jaws be either farther apart or nearer together, and, in order to have the handle occupy much the same desirable operating or angular position as before, it may be necessary to shift the ful- 10 crum-pin into one or the other of the remaining bearings. This is done by grasping the opposite ends of the pin with the thumb and forefinger, turning it to bring its flattened part of reduced cross-sectional dimen- 15 sion into register with the connecting slot, causing the pin to traverse such slot and enter the desired bearing, and then rotating the pin in such bearing to destroy the register of its flattened part with the connecting 20 passages, whereupon the handle can be turned on the fulcrum-pin in the usual way without danger of disarrangement of the parts.

The positions of these bearings are so 25 chosen that there are no gaps in the operative dimensions between the jaws over the whole range of movement of the slidable jaw, and it is also of advantage to have the operative range of movement of the reciprocatory jaw for any position of the fulcrum-pin overlap that of the jaw when the pin is in the next bearing, either way, so that for nuts of certain sizes covered by such 30 overlapping ranges the handle may occupy either one of two positions, dependent upon 35 which one of the two bearings in question is occupied by the pin.

Furthermore, regardless of which bearing the pivot-pin is in, the handle may be swung 40 around to the right sufficiently to free its end 26 entirely from its bearing 27, thus permitting the sliding jaw to be wholly removed from the device and a different one substituted if desired.

45 It will be appreciated, therefore, that the wrench is usable through a wide range of dimensions of the articles operated upon with the handle, by reason of the change of position of the fulcrum-pin, always in a convenient position for favorable and powerful action.

In some cases it is desirable to have the fulcrum or pivot-pin operable by the handle itself rather than independently and accordingly in Fig. 3 I have shown such a construction. This structure is practically the 55 same as the other except that the pivot-pin 32, flattened as in the other case, is rigid with or fixed to the handle 33. When, therefore, it is desired to transfer the pin from one bearing to another the handle is turned to bring its flat part into alinement with the connecting slot through which it is pushed by the handle to the next bearing. When 60 the handle is in natural or normal jaw-op-

erating position, however, the pin and slots are out of register and the pin cannot leave the bearing which it then occupies.

In the device of Fig. 4, the same general idea is carried out in the form of pliers with 70 double handles 34 and 35, the former integral with the bifurcated jaw member and the latter corresponding to the oscillatory handle of the other appliances. In this case the fulcrum or pivot-pin 36 may be rigid 75 with, or turn with relation to, the handle-member or lever 35, all as has been fully explained above.

It is to be understood that the invention 80 is not limited and restricted to the precise and exact features of construction presented because these may be varied within comparatively wide limits without departure from the heart and essence of the invention and without the sacrifice of any of its substantial 85 benefits and advantages. For example, the number of bearings provided for the pivot-pin may be either increased or decreased from those shown in the drawings and various other features of structure may 90 be more or less modified as occasion demands and as will be apparent to those skilled in this industry. It will be appreciated, furthermore, that it is comparatively immaterial whether the bearings are in the member carrying the fixed or stationary jaw and the fulcrum-pin, associated with the lever, movable from one bearing to the other, or whether the fulcrum-pin is fixed to the stationary jaw member and the connected bearings therefor are present in the lever or handle, but the former construction is to be preferred, and consequently this is the type 95 illustrated in detail in the drawings and described above. Such modified structure, 100 however, is deemed to be an equivalent of those presented in the appended claims.

I claim:

1. In a wrench of the character described, the combination of a bifurcated member 110 having a fixed clamping-jaw, a companion sliding clamping-jaw movable toward and from said first jaw and having a base-portion accommodated in the bifurcated part of said member, an operating lever having a 115 direct rocking connection with said base-portion, and a fulcrum-pin fixed to and projecting from opposite sides of said lever, each of such projections having a reduced transverse dimension, the spaced walls of 120 said bifurcated member having a plurality of registering bearings for said fulcrum-pin, the bearings of each wall being connected together by one or more narrower 125 passages, whereby said pin may occupy and be retained in any pair of said bearings and act as a fulcrum for said operating-lever and may be shifted to any other pair of bearings by reason of said reduced dimensions which permit it to pass through said 130

connecting passages when in register therewith, substantially as described.

2. In an appliance of the character described, the combination of a handle-member having a bifurcated portion provided with a fixed clamping-jaw, a companion sliding clamping-jaw movable toward and from said first jaw and having a recessed base-portion accommodated in the bifurcated 10 part of said member, an operating-lever having a rounded end fitted in said recess, and a fulcrum-pin fixed to and projecting from opposite sides of said lever each of such projections having a reduced transverse 15 dimension, the spaced walls of said bifur-

cated portion of the handle member having a plurality of registering bearings for said fulcrum-pin, the bearings of each wall being connected together by one or more narrower passages, whereby said fulcrum-pin may occupy and be retained in any pair of said bearings and act as a fulcrum for said operating-lever and may be shifted from any pair of said bearings to any other pair by reason of said reduced dimensions which 20 permit it to pass through said connecting passages when in register therewith, substantially as described. 25

ALLEN C. ALLAN.
